METHOD AND APPARATUS FOR COATING
PAPER AND THE LIKEAdolph Potdevin, Garden City, N. Y., assignor to
Potdevin Machine Company, Brooklyn, N. Y.,
a corporation of New York

Application June 1, 1935, Serial No. 24,474

16 Claims. (Cl. 91—70)

This invention relates to an improved method of and apparatus for coating paper and the like and is particularly directed to the manufacture of wax paper.

5 My invention contemplates the application of wax to a traveling web of paper or the like in a heated tank from which the web continues its travel to a bath of cooling water or other liquid; upon further travel of the web the cooling liquid 10 is removed and the web dried by air and vibration of the web.

In the accompanying drawing wherein I have illustrated a device for carrying out my invention:

15 Fig. 1 is a perspective view of my improved apparatus; and

Fig. 2 is a view partly in section of the drying mechanism.

Referring to the drawing in detail, 1 designates 20 a supply roll from which the web of material to be coated may be withdrawn in any suitable manner. The web is drawn through a tank 2 containing wax or other coating material which may be heated if necessary in any suitable manner. 25 In its passage through the tank 2 the material is drawn under roller 3 and then over roller 4, between it and another roller above it designated 5. The rollers 4 and 5 I shall designate surfacing rollers, the coating material being spread and 30 levelled on the web by these rollers and surplus coating material removed.

The web is drawn from between the surfacing rollers 4 and 5 through a tank 6 containing cooling fluid and where the web passes beneath a 35 roller 1 which is provided in this tank. The cooling fluid which may be water, for example, cools and sets the wax or other coating material.

During this part of its travel the web has been caused to travel vertically over a roller 8 which is 40 mounted a suitable distance above the discharge end of the cooling tank 6.

On its passage to the roller 8 the web is drawn past a drying station, comprising a blower 9 the discharge side of which is provided with a conduit 10 which terminates in a fork consisting of a pair of perforated conduits 11 and 12 closed at their outer ends. The web in its vertical travel to the roller 8 passes through this fork, and the perforations 13 in each of these conduits are on 45 the sides of the conduits adjacent the web. In addition to the perforations 13 each of the conduits 11 and 12 is provided with a longitudinal spout or nozzle 14 sloping downwardly toward the opposed faces of the web.

50 At each side of the web, below the conduits 11

and 12, I provide rotary cooperating paddles 16 and 17, extending the width of the web and driven by a motor 18 through a belt 19, the paddles being geared to each other so as to rotate toward the web, by gears 20 and 21.

With the paddles 16 and 17 in rotation air from the blower 9 is blown through the conduits 11 and 12 and out through the perforations 13, and at the same time through the nozzles 14 against each side of the traveling web.

5 The paddles 16 and 17 being offset, circumferentially, with respect to each other, and rotating in opposite directions, toward the faces of the web, it will be evident that with the parts in the position shown in Fig. 2, air from the left hand nozzle 14 is blown down along the face of the web and is partially pocketed between the two blades 18 and 19 so as to exert lateral pressure upon the web in a direction to force the web to the right, to the full line position shown in Fig. 2. At this 10 same time air is issuing from the right hand nozzle 14 upon the right hand face of the web, but owing to the position at this instant, of the blades 20 and 21 of the paddle 17, the lateral pressure on the right hand face of the web is less than that on the opposite face, with the result that the web is deflected as shown in full lines in Fig. 2. On continued rotation of the paddles, it will be apparent that conditions will be reversed, and the web will be deflected in the other direction to the 15 dotted line position of Fig. 2. It will be apparent, therefore, that the web will be vibrated out of the plane of both faces, a motion such as would be imparted to the web if shaken by hand. This 20 will obviously blow and shake off the excess cooling liquid, bearing in mind that the nozzles 14 are directed downwardly so that the air issuing therefrom tends to pass downwardly along the face of the web. As the web, freed of its surplus 25 cooling liquid, passes between the perforations 13 of the air nozzles, through which air is discharged directly against the face of the web, it will be 30 instantly evaporated so that the web is now in the desired dry condition.

35 It will be noted from Fig. 2 that the web is not 45 engaged by the blades of the paddles 16 and 17 or by the conduits 11 and 12, so that there will be no scratching or scraping of the waxed surface of the web.

40 While I have illustrated and described one embodiment of a device for carrying out my improved method, it is to be understood that various changes and modifications may be made therein without departing from the spirit and scope of 45 my invention.

What I claim is:—

1. The method of coating paper and the like, which method comprises continuously moving a web of the material through a bath of coating material, advancing the web to a bath of cooling fluid to cool the coating and then moving the web between air streams directed alternately first against one side and then against the other side to vibrate the web to remove excess cooling fluid and dry the coated web.
2. The method of coating a web of material, which method comprises applying a coat of molten coating material to the web, cooling the coating material on the web by passing the coated material through a bath of cooling fluid, then so applying an air stream to each face of the web alternately to impart a vibratory motion to the web to rid the same of excess cooling fluid.
3. The method of waxing paper, which comprises continuously moving a web of paper through a bath of molten wax to apply a coating thereto, advancing the web through a bath of cooling water to cool the wax coating and then moving the web between air streams to dry the same and simultaneously directing alternate air blasts to each face of the paper to vibrate the web to remove excess cooling water.
4. The method of making wax paper, which comprises applying a coat of molten wax to the web, cooling the wax on the web by passing the web through a bath of cooling liquid, then applying a stream of air to each of the faces of the web and causing the air to be deflected alternately at each side against the web so as to impart a vibratory motion to the web to shake off excess cooling liquid.
5. In an apparatus for coating a web of material, which comprises a bath of molten coating material, a bath of cooling fluid, and means for drawing the material through said baths in the order named, the combination of means including air streams at each side of the web and air deflecting means cooperating with the said air streams for imparting vibratory motion to the web to rid the same of excess coating fluid.
6. In an apparatus of the class described, comprising a bath of coating material, a bath of cooling fluid, and means for continuously advancing a web of material to be coated through said baths, the combination of air conduits on each side of the web following the cooling bath, a discharge nozzle for each of said conduits directed toward opposite faces of the web, means for supplying air to said conduits, and means for alternately deflecting the air streams from said nozzles against each face of the web thereby to impart a vibratory motion to the web to remove excess cooling fluid therefrom.
7. In an apparatus of the class described, comprising a bath of coating material, a bath of cooling fluid, means for passing a web of material to be coated continuously through said baths, the combination of perforated air conduits on each side of the web beyond the cooling bath through which air is passed to each side of the web, nozzles for each of said conduits sloping downwardly toward the web, means for supplying air to said conduits, and means for deflecting the air streams from said nozzles against alternate faces of the web to impart a vibratory motion to the web to remove excess cooling fluid from the web.
8. In an apparatus for making wax paper, comprising a tank of molten wax, a tank of cooling liquid, means for continuously advancing a paper web through said tanks, the combination of means

including an air stream and air deflecting means at each face of the paper for vibrating the paper after the same leaves the said last mentioned tank to rid the web of excess cooling fluid.

9. In an apparatus for coating a web of material, comprising a bath of coating material, a bath of cooling liquid, means for advancing the material successively through said baths, the combination of air conduits on each side of the web beyond the cooling bath, nozzles for each of said conduits directed toward the web, said conduits and nozzles being out of contact with the web, means for supplying air to said conduits and means for deflecting the air streams from said nozzles first against one side of the web and then against the other thereby to impart a vibratory motion to the web to remove excess cooling liquid from the web.

10. In an apparatus for making wax paper, comprising a bath of coating material, a bath of cooling liquid, continuously advancing a web to be coated through said baths, the combination of perforated air conduits spaced from the web and located beyond the cooling bath through which air is passed to dry each side of the web, nozzles in each of said conduits directed downwardly toward the web faces, means for supplying air to said conduits, and means for alternately deflecting the air streams from said nozzles first against one side of the web and then against the other thereby to vibrate the web to remove excess cooling fluid therefrom.

11. In paper waxing apparatus, comprising a supply roll of paper, an open tank of molten wax, a guide roller in said tank, a pair of superimposed surfacing rollers, means for continuously drawing the paper web from said supply roll under said guide roller and between said surfacing rollers, a tank of cooling water, a roller therein, said web passing continuously from said surfacing rollers under the roller in said water tank, the combination of air tubes, one at each side of said web, beyond the cooling tank, each having air outlets on the side adjacent the face of the web, means for supplying air to said tubes and rotating members for causing a deflection of the air from said tubes against alternate faces of the web, to vibrate the web.

12. In paper waxing apparatus comprising a supply roll of paper, an open tank of molten wax, a guide roller in said tank, a pair of superimposed surfacing rollers, means for drawing the web of paper from said supply roll and continuously advancing the same under said guide roller in the bath of molten wax and then out of the tank and between said surfacing rollers, a tank of cooling water, a roller therein, said web passing from said surfacing rollers under the roller in said water tank where the wax is cooled, the combination of an air tube at each side of said web, located beyond the cooling tank, and having nozzles extending longitudinally of the air tubes and projecting downwardly at an angle toward the web, means for supplying air to said tubes, rotating members for effecting intermittent deflection of the air from said tubes to vibrate the web, and means for driving said rotating members.

13. In paper waxing apparatus comprising a supply roller of paper, an open tank of molten wax, a guide roller submerged in said tank, a pair of superimposed surfacing rollers, means continuously to draw paper from said supply roll and pass the same under said guide roller and between said surfacing rollers, a tank of cooling

water, a roller therein, said web passing from said surfacing rollers under the roller in said water tank to cool the wax on the web, the combination of an air line, a blower connected thereto, said line terminating in a pair of spaced air tubes, one at each side of said web, said tubes being perforated at the sides adjacent the web faces and having air nozzles extending longitudinally of the tubes and projecting downwardly at an angle toward said web, and paddles at each side of the web adjacent said tubes and so positioned as to deflect the air from said nozzles in its passage against the web, the paddle blades at one side of the web being offset with respect to the paddle blades at the other side of the web to effect deflection of the air against alternate web faces thereby to vibrate the web to rid the same of excess cooling water.

14. In coating apparatus comprising a bath of coating material, a bath of cooling fluid, means for drawing a web of the material to be coated continuously through said baths, the combination of means for applying an air stream to both faces of the advancing web after it has left the cooling bath, and means intermediate the air-applying means and the cooling bath, cooperating with the air streams to effect deflection thereof in a direction to cause lateral vibration of the web out of the plane of each face thereof.

15. In coating apparatus comprising a bath of coating material, a bath of cooling fluid, means for continuously advancing a web to be coated successively through said baths, means for effecting further advance of the web in an upward direction, the combination of means for applying an air stream in a downward direction against each face of the upwardly moving web, and deflecting means for deflecting the air against each face of the web alternately to vibrate the web and 10 rid the same of surplus cooling fluid.

16. In coating apparatus comprising means for applying coating material to a continuously advancing web of material to be treated, means for applying a cooling fluid to the coated material, 15 web guiding means for effecting upward travel of the web after the cooling operation, the combination of means for applying an air blast against each face of the upwardly traveling web contrary to the direction of travel of the web and a pair 20 of vanes rotatable toward the web adjacent each face thereof, said vanes being offset circumferentially with respect to each other, and adapted to pocket some of said air alternately at each side 25 of the web, thereby causing deflection of the web first in one direction, and then the other out of the plane of its faces, to rid the web surface of excess cooling fluid.

ADOLPH POTDEVIN.
